UNITED STATES PATENT OFFICE.

PETER H. PETERSON, OF RACINE, WISCONSIN, ASSIGNOR TO GOLD MEDAL CAMP FURNITURE MANUFACTURING COMPANY, OF RACINE, WISCONSIN, A CORPORATION OF WISCONSIN.

COLLAPSIBLE COT.

1,269,641.

Specification of Letters Patent. Patented June 18, 1918.

Application filed January 4, 1917. Serial No. 140,484.

To all whom it may concern:

Be it known that I, PETER H. PETERSON, a citizen of the United States, residing at Racine, in the county of Racine and

5 State of Wisconsin, have invented certain new and useful Improvements in Collapsible Cots, of which the following is a specification, reference being had to the accompanying drawing, forming a part thereof.

10 This invention relates to collapsible or folding cots and the objects of the invention are to improve the construction of such cots in the manner to be hereinafter described and claimed.

15 Referring to the drawings which accompany this specification and form a part hereof, on which drawings the same reference characters are used to designate the same parts wherever they may appear in 20 each of the several views, and which drawings illustrate an embodiment of this invention, Figure 1 is a lengthwise elevation of the cot; Fig. 2 is an end elevation of the cot; Fig. 3 is an elevation of the legs of the 25 cot and parts permanently connected therewith in their collapsed or folded positions; Figs. 4 and 5 are perspective views, on an enlarged scale, of details of construction; and Fig. 6 is an elevation of one of the side 30 bars in collapsed or folded position.

Referring to the drawings the reference numerals 1, 2, 3, 4, 5, 6, 7 and 8 designate legs which are pivotally connected in pairs so that the legs of each pair can be collapsed 35 or folded parallel with each other or unfolded to stand like the letter capital X. Each set of legs is connected with the next adjacent set of legs by braces on both sides of the cot. Only some of the braces are 40 shown by the drawings and they are designated by the reference numerals 9, 10, 11, 12, 13, 14, 15 and 16. The braces are all connected in pairs by pivots and the pivots which are shown by the drawings are des- 45 ignated by the reference numerals 17, 18, 19 and 20. Each leg is provided with two hinge members on opposite sides thereof, one of which is located near the top of the leg and the other of which is located near the 50 bottom of the leg. Only some of these hinge members are shown by the drawings and they are designated by the reference nu-

merals 21, 22, 23, 24, 25, 26, 27, 28, 29 and 30. The hinge members are pivotally connected or hinged to the legs by pivots or rivets 55 which are designated on the drawings by the common reference character 31. These hinge members are preferably duplicates of each other to minimize the cost of production and their construction is clearly shown 60 by Figs. 4 and 5 of the drawings. The braces are connected with the hinge members by links which are pivoted both to the braces and to the hinge members. These links are designated on the drawings by the 65 common reference numeral 32 and they are pivoted to the hinge members by the pivots 33 and to the braces by the pivots 34. Two braces are connected with each end of each leg of the intermediate sets of legs and it is 70 preferred to connect each two braces with a single link as clearly shown by the drawings.

The upper end of each leg is provided with a hook 36 which may be secured to the 75 leg in any suitable manner, as, for example, by rivets 35 and the side bars 38 are provided with staples 37 which are adapted to be engaged with the hooks 36.

The side bars 38 are made in sections 80 which are connected with hinges 39 and are slipped into hems 40 at the edges of the cover 41. The staples 37 project out through slits in the canvas cover as clearly shown by Fig. 2 of the drawings. It will be readily 85 apparent from an inspection of the drawings that the cover 41 and side bars 38 can be removed from the legs and folded up and that the legs and braces can be readily collapsed or folded into the positions shown by 90 Fig. 3 of the drawings so that the cot can be collapsed and folded into a comparatively small package for transportation or storage.

The links 32 which connect the braces with the hinge members secured to the legs permit 95 movement of any brace on one side of the cot to be communicated to all of the other braces on the same side of the cot in a manner which will be readily understood.

What is claimed is:—

1. In a collapsible cot, the combination with legs pivotally connected in pairs and provided with hinge members, of braces pivotally connected in pairs, and links pivotally

connected to said braces and to said hinge members.

2. In a collapsible cot, the combination with legs pivotally connected in pairs, of 5 hinge members pivotally connected to the tops and bottoms of said legs, braces pivotally connected in pairs, links pivotally con-

nected with said braces and said hinge members, two braces being connected with the links connected with the legs intermediate 10 the end legs.

In witness whereof I hereto affix my signature.

PETER H. PETERSON.
